UNITED STATES PATENT OFFICE.

JOHN WESLEY LEWELLEN, OF RIDAL, AND FRANK P. HOMER, OF ALDAN, PENNSYLVANIA.

HEADLIGHT.

1,222,427.

Specification of Letters Patent. Patented Apr. 10, 1917.

Application filed September 21, 1915. Serial No. 51,841.

To all whom it may concern:

Be it known that we, JOHN WESLEY LEWELLEN and FRANK P. HOMER, residents, respectively, of Ridal, Montgomery county, Pennsylvania, and Aldan, Delaware county, Pennsylvania, citizens of the United States, have invented certain Improvements in Headlights, of which the following is a specification.

- 10 One object of our invention is to provide a novel combination of parts particularly designed for use in headlights, whose construction shall be such as to prevent an objectionable glare above a substantially horizontal plane passing through the reflector axis, while giving the fullest illumination of the ground surface or other objects below said plane.

It is also desired to provide a simple and inexpensive headlight including a device for cutting off the greater part of the rays of light emitted from the reflector in lines extending above a horizontal plane passing through the center of the reflector, while permitting the utilization of a maximum part of the reflector surface for directing light rays upon objects to be illuminated, below this plane; the invention also contemplating novel means for retaining in place 30 a screen which is usually made of frosted or ground glass, together with a novel arrangement and mounting for a secondary screen.

These objects and other advantageous ends we secure as hereinafter set forth, reference being had to the accompanying drawings, in which,

Figure 1 is a front elevation of a headlight constructed according to our invention; and

Figs. 2 and 3 are sections taken respectively on the line *a—a* and *b—b*, Fig. 1.

In the above drawings 1 represents the curved body of the reflector which preferably is given the form of a paraboloid surface having a source of light such as the lamp 2 mounted with its filament at or adjacent its principal focus. Mounted within the reflector in a plane at right angles to the axis thereof is a circular glass plate 3 held in place by clips 5 soldered to or struck up from the reflector surface. That part 6 of the plate above a horizontal plane passing through the reflector axis is transparent or

perfectly clear, while the remainder which is below said plane, is frosted in any suitable manner as indicated at 7 so that it is translucent.

Fixed to the curved reflector surface immediately in front of the bottom of the glass plate 3 is a bracket 8 having lugs to which a rod 9 is pivoted by a suitably mounted pin 10. This rod is held substantially parallel with and adjacent the plate 3 by a set screw 11 which passes through it into a short lug 12 projecting from the bracket 8, and a flat metal or other suitably formed spring 13 is mounted between the bracket 8 and the plate 3 so as to hold the latter from rattling. The upper end of the rod 9 carries a clamp 14 in which is mounted an elongated and substantially rectangular frosted glass plate 15 which is supported in a plane substantially parallel with that of the plate 3 and a short distance in front of the same.

This auxiliary or secondary screen 15 is in such position that its lower edge is practically coincident with the horizontal plane passing through the focus of the reflector and its height is such that it effectually cuts off any light rays directed upwardly from the lower part of the reflector owing to its departure from a true parabolic curvature. Obviously the length of this secondary plate or screen may be somewhat varied although it is preferably about half the diameter of the reflector opening.

Under conditions of use, while certain of the direct rays from the source 2 can pass through the clear part 6 of the glass plate 3, above the upper edge of the secondary screen 15, the latter intercepts such of the rays which are directed upwardly from the lower half of the reflector above the top edge of the frosted portion 7. Obviously if the length of the lower part of the clear section 6 were frosted to a height equal to the height of the secondary screen 15, approximately the upper quarter of the side parts of the reflecting surface 1 would be rendered inoperative since they could not receive any direct rays of light from the source. However by supporting the secondary screen 15 some distance in front of the main screen plate 3, these upper side portions receive direct light rays and reflect them outwardly. The reflector constructed as illustrated, when viewed from the front by an observer whose

2
 eyes are above the horizontal plane passing through the lamp 2, presents a translucent lower portion which when the lamp 2 is in operation, presents a glowing appearance 5 which is not objectionable nor blinding, and with the secondary screen 15 placed as shown, any light rays reflected above the top edge of the part 7 are cut off. As a consequence those rays from the source which are 10 reflected through the clear portion 6 of the plate 3, are directed downwardly below or parallel with a horizontal plane passing through the lamp, thus giving the desired illumination of a roadway and other objects 15 below this plane, upon which the head-light is directed. It is noted that the direct rays of light passing out of the reflector in lines below the top edge thereof and above the top edge of the secondary screen 15, are not sufficient 20 to cause any objectionable glare or blinding effect, so that the driver of a car approaching such a head-light as that illustrated, or a pedestrian on whom the head-light is directed, is enabled to clearly see 25 the fully illuminated road-way without experiencing the blinding glare which characterizes headlights as ordinarily made.

It is to be noted that without departing from our invention the plate or piece 3 constituting the primary screen may have its 30 parts 6 and 7 made structurally independent although in some cases it may be advantageous to employ a single piece disk whose upper half is transparent and whose lower half is frosted. When for any reason it is necessary to remove or repair the primary screen, the screw 11 may be disengaged from the lug 35 12 and the rod 9 swung down through an angle of 90 degrees, so that neither it nor the secondary screen will interfere with the 40 work on the main screen.

Obviously in some cases the top part 6 may be altogether omitted since it has no optical function,—although preferably employed either as an independent piece or integral with the bottom member 7.

We claim:—

1. The combination with a concave reflector of a source of light; a main screen of 50 which a portion only is transparent; and an auxiliary screen of translucent material mounted in front of said transparent portion of the main screen; the height of said auxiliary screen being sufficient to cut off 55 rays of light reflected in lines extending

above a horizontal plane passing through the axis of the reflector.

2. The combination with a concave reflector of a source of light therefor; a main screen of which a portion only is transparent; and an auxiliary screen of translucent material mounted in front of said transparent portion of the main screen; the length of said auxiliary screen being at most 60 insufficient to cut off direct rays of light 65 from the source to the outermost side portions of the reflector.

3. The combination with a concave reflector of a source of light; a main screen of which one portion is transparent and the other portion is translucent; with an auxiliary screen of translucent material mounted in front of the transparent part of the main screen and extending to a height sufficient 70 to cut off practically all rays of light reflected above a horizontal plane passing through the focus of the reflector while permitting passage of those rays of light reflected parallel with or downwardly toward 75 said plane.

4. The combination with a concave reflector of a source of light; a main screen therefor; and an auxiliary screen mounted in front of the main screen but adjustable 80 forwardly to permit removal of the latter.

5. The combination with a concave reflector of a main screen; a standard pivotally mounted in front of said screen and adjustable on its pivot from such position 85 through an angle of substantially 90 degrees; with an auxiliary screen carried by 90 said standard.

6. The combination of a concave reflector; a substantially circular glass screen mounted between its focus and its open end; and a laterally elongated secondary screen mounted 95 above a horizontal plane passing through the reflector axis in front of said main screen.

7. The combination of a concave reflector; a main screen mounted therein; a bracket in 100 front of the main screen; a secondary screen carried by said bracket; a standard also carried by the bracket; with a laterally elongated auxiliary screen supported by said standard in a plane parallel with that of the 105 main screen adjacent the central portion thereof.

JOHN WESLEY LEWELLEN.
FRANK P. HOMER.
